ABSTRACT OF THE DISCLOSURE

A multilayered radiant energy responsive display device including a light transmitting base, a first electrode, an electroluminescent layer, an interlayer, a photoconductive layer, a third electrode, an impedance layer, a second electrode, and power supply means. The impedance layer being an energy converting luminescent layer having a radiant energy response to a first spectral distribution and having a luminescence characteristic with a second energy distribution different from the first and at least partly overlapping the spectral photoconductivity distribution of the photoconductive layer whereby, when excited by radiant energy, the luminescent layer produces luminescent light energy to which the photoconductive layer is responsive.

This invention relates to radiant energy responsive display devices and particularly to those of the type including a photoconductive layer, an electroluminescent layer lying on one surface of said photoconductive layer with an intermediate layer such as an opaque layer interposed therebetween if required, an impedance layer lying on the other surface of said photoconductive layer, a first, light-transmitting electrode arranged on the outer surface of said electroluminescent layer, a second, radiant-energy transmitting electrode arranged on the outer surface of said impedance layer, a third grid-like electrode including a wire, ribbon or reticular electroconductive structure and interposed between said electroluminescent and impedance layers in electrical contact with said photoconductive layer, electric power supply means for impressing a voltage V_1 between said first and third electrodes and another voltage V_2 between said first and second electrodes, said voltages V_1 and V_2 being variable or fixed at least in voltage value or polarity where they are fed in DC form and at least in amplitude or phase where they are fed in AC form, and means for electrically controlling the luminescence intensity of said electroluminescent layer through the variation in impedance under the excitation of the radiant energy on said photoconductive layer thereby to convert the radiant energy image into visible form on said electroluminescent layer with or without amplification.

The radiant energy responsive display device has conventionally been called an electrostatic image converter-amplifier. For discrimination between the inventive and conventional devices, however, only the latter will conveniently be called an electrostatic image converter-amplifier throughout the following description.

The electrostatic image converter-amplifier employs a so-called second electrode and an impedance layer which are both transmissive to radiant energy. With such device, it has been found and made known by the inventor that, by properly selecting or fixing the voltages V_1 and V_2 , the radiant energy image impinging upon the photoconductive layer can be converted with or without amplification into a visible image of the positive, negative or

2

mixed nature on the electroluminescent layer and that, by controlling the voltages V_1 and V_2 , the contrast ratio, gamma and other operating characteristics of the device can be made variable over a wide range.

Moreover, with the positive image amplification characteristic, which produces an image of the positive nature, the radiant energy displayed can be stored with a bistable luminescence intensity by feeding the luminescent rays from the electroluminescent layer back to the photoconductive layer.

On the other hand, the photoconductive layer employed in the electrostatic image converter-amplifier is subject to limitations due to its material nature. For example, the spectral response distribution of the photoconductive layer is held within considerably narrow limits because of its properties deriving from the material of which the layer is formed and usually the layer is utterly non-responsive or only slightly responsive to some forms of radiant energy.

To cite an example, photoconductive materials of the type previously used most widely include cadmium sulfide and cadmium selenide both activated with copper, chlorine, etc. and solid solutions of cadmium sulfide and cadmium selenide. The spectral photoconductivity distribution of this type of photoconductive material ranges from about 500 $\text{m}\mu$ to 900 $\text{m}\mu$, only partly covering the visible light range. The range of distribution may be further limited under conditions of preparation for such material. Thus, the photoconductive layer formed of such material is entirely non-responsive to light rays of the wavelength of less than 500 $\text{m}\mu$ and also to ultraviolet rays. To the radiant energy of X-ray levels the material exhibits some sensitivity, which is very limited when compared with the sensitivity to radiant energy in the visible and near infrared regions. In addition, because of the high penetrability, X-ray radiation is transmitted through the photoconductive layer effecting only a limited amount of excitation thereto. This is the reason why the layer exhibits an extremely limited sensitivity to X-ray radiation.

As for the electron radiation, for example, taking the form of a beam of electrons, it is blocked by the impedance layer, which customarily takes the form of a solid layer. Thus, it has been impossible to excite the photoconductive layer by electron radiation because of the structure of the display device.

The present invention is intended to overcome these difficulties.

According to the present invention, there is provided a radiant energy responsive display device of the type described in which the impedance layer is a luminescent impedance layer responsive to radiation energy including a single, mixed or composite layer having a radiant energy responsive luminescence characteristic at least partly overlapping the spectral photoconductivity distribution of the photoconductive layer whereby, when excited with radiant energy, said impedance layer produces luminescent light energy to which the photoconductive layer is responsive.

According to the present invention, the photoconductive layer can be effectively excited by properly selecting the luminescent or fluorescent material for forming the radiant energy responsive luminescent impedance layer to effectively convert radiation energy into light energy to which the photoconductive layer is most sensitive.

According to the present invention, it will be appreciated, therefore, that the display device is operable with high sensitivity even to radiant energy of the level to which conventional electrostatic image converter-amplifiers have been inoperable or operable only with limited sensitivity because of the structure of the photoconductive layer. Moreover, the inventive device is extremely

simple in construction and highly efficient since it includes a radiant energy responsive luminescent impedance layer which apparently serves also as an impedance layer essential to conventional electrostatic image converter-amplifiers.

The foregoing and other objects and features of the present invention will become apparent from the following description when taken in conjunction with the accompanying drawings, which diagrammatically illustrate some embodiments of the invention. In the drawings:

FIG. 1 is a diagrammatic view of one embodiment of the present invention including a luminescent impedance layer in the form of a single or mixed layer, illustrating its structure and the power supply system therefor;

FIG. 2 is a diagrammatic illustration of the embodiment as used with radiant energy in the form of a beam of electrons;

FIG. 3 is a cross-sectional diagram of another embodiment of the invention, which includes a luminescent impedance layer in the form of a composite layer, illustrating its structure and the power supply system therefor; and

FIG. 4 illustrates a modification of the embodiment shown in FIG. 3, which further includes a DC control.

In the drawings, like reference characters indicate like parts throughout the several figures for the sake of convenience, though in some figures the parts are omitted or shown on an enlarge scale. In the following description, the radiant energy responsive luminescent impedance layer will be referred to briefly as a luminescent impedance layer.

FIG. 1 diagrammatically illustrates the structure of a radiant energy responsive display device according to the present invention and a power supply system therefor which are usable with radiant energy in the form of radiation such as X-rays, γ -rays or an electron beam.

In FIG. 1, the reference numeral 1 indicates a light-transmitting base or support plate, for example, formed of transparent glass sheet; and reference numeral 2 indicates a first electrode which is light-transmitting and formed, for example, of a metal oxide such as tin oxide.

The reference numeral 3 indicates a electrode-luminescent layer which includes a vapor-deposited film such as of ZnS or a mixed layer formed, for example, of ZnS powder activated with copper for green luminescence and bound with glass enamel, plastic or the like material. The electroluminescent layer 3 is a solid layer having a thickness of the order of from 5 to 70μ and emits light when excited electrically. An opaque interlayer 4 is arranged so as to prevent any unstable operation of the device which may otherwise be caused by the excitation of a photoconductive layer 5 by the light feedback from the layer 3 or exterior light arriving from the base side of the device. The interlayer 4 is a solid high-resistance layer of the thickness of the order of 1 to 10μ , which includes an evaporated film of an opaque high resistance material or is formed of a black paint, carbon black or the like material and a binder such as plastic or glass enamel. The photoconductive layer 5 includes a powder of photoconductive substance such as CdS activated with copper or chlorine and bound with plastic, glass enamel or the like binder material into layer form, or an evaporated film of such photoconductive substance including no binding agent, or also a sintered film of such substance. The layer 5 has a thickness of the order of from 5 to 100μ , and, containing CdS as an essential element, as described above, exhibits a high sensitivity to the excitation of orange and infrared light energy with decreasing resistance. The reference numeral 6 indicate a grid-like third electrode, which in this embodiment is recticular. The grid-like third electrode 6 includes a continuous metal structure like that of a metal net electrode such as used in television pickup tubes, which includes conducting sections having a width of the order of, say 10 to 30μ and a thick-

ness of the order of, say, several microns arranged in about 50 to 100 mesh. Alternatively, the electrode 6 may be of a discontinuous metal structure including tungsten or other metal wires of the thickness of the order of, say, 10 to 30μ , weaved into a network of 50 to 100 mesh or arranged so as to cross each other to obtain a reticular formation. If necessary, the wire elements may previously be plated with gold or other metal. The third electrode 6 is arranged in electrical contact with the photoconductive layer 5.

The reference numeral 100 indicates a luminescent impedance layer which takes the form of a single or mixed layer. For radiant energy E_1 in the form of an electron beam, the luminescent impedance layer 100 is formed of a fluorescent material such as $(Zn, Mg)F_2$ for cathodoluminescence; and, for radiation energy E_1 , for example, in the form of X-rays or γ -rays, the layer 100 is formed of a fluorescent material for radiation luminescence such as ZnCdS:Ag, which emits orange light energy to which said photoconductive layer 5 is responsive with the highest sensitivity.

One form of such luminescent impedance layer is comprised of a mixed layer formed of powdery luminescent or fluorescent material such as described above mixed with a binding agent such as epoxy resin or glass enamel, and is particularly suitable for use with X-rays, γ -ray or like radiant ray.

Another form of luminescent impedance layer includes a single layer of fluorescent material of the type described above formed by vapor depositing or a single layer formed by precipitating the fluorescent material preliminarily suspended in a solution of an appropriate cellulose such as nitrocellulose in a suitable organic solvent such as aluminum acetate and baking the layer of precipitate to vaporize the organic substances included therein while causing the precipitate to cohere together to form a desired single layer, which is particularly well adapted for use with electron beams.

The luminescent impedance layer formed in the manner described above has a high resistivity and exhibits a capacitive impedance to AC voltages and when excited with radiant rays or an electron beam emits orange light, to which the photoconductive layer 5 is responsive with high sensitivity. The thickness of the luminescent impedance layer 100 should be determined in due consideration of its relationship with the impedance of the other layers and of its characteristics relative to the radiant energy, including its transmissivity, dielectric strength and impedance. For example, the thickness of the layer 100 is determined on the order of from 20 to 200μ , depending upon the dimensions of the other layers cited hereinbefore.

The reference numeral 7 indicates a second electrode which is transmissive to radiation energy. For radiation E_1 in the form of an electron beam, the electrode 7 preferably includes a thin evaporated film of metal such as aluminum. For radiation E_1 in the form of X-rays or the like radiant rays of high penetrability, the electrode 7 is formed of a similar evaporated film of aluminum or a thin film of aluminum or the like metal.

The second electrode 7 formed in the manner described above is transmissive to radiant energy and highly reflective to the luminescent light energy as emitted from the layer 100 when the latter is excited with radiation energy so that the light energy is effectively prevented from escaping exteriorly through the electrode 7 and reflected toward the layer 5. Thus, excitation of the photoconductive layer 5 can be effected with high efficiency by the luminescent light energy.

For radiations in the form of X-rays, γ -rays or like radiant rays, the second electrode 7 may include an electrically conductive coated layer such as of silver paint.

The electrical power supply may be performed, for example, in the manner shown in FIG. 1. In the case where the electroluminescent layer 3 is formed of a

powder of electroluminescent material such as $ZnS:Cu, Al$, which emits green light when excited, and a binding agent such as epoxy resin, an AC power supply source is connected to the device since the layer 3 is luminescent only when excited by an AC voltage. The third electrode 6 includes a conductive strip 17 and an AC power source 8 is connected between the strip 7 and the first electrode 2 by conductor means 9 and 10 so that an AC voltage V_1 is applied between electrodes 2 and 6.

On the other hand, an AC power source 11 is connected between the first and second electrodes 2 and 7 by way of conductors 9 and 12 to apply an AC voltage V_2 of the same frequency as the voltage V_1 between the electrodes 2 and 7.

Under this condition, assume that $V_2=0$ with the electrodes 2 and 7 short-circuited through an external circuit and the frequency of voltage V_1 is selected on the order of 100 to 5000 cycles per second at an appropriate voltage value. If the device is irradiated with an X-ray energy image E_1 , the luminescent impedance layer 100 is excited to emit light which effectively excites the photoconductive layer 5, and simultaneously the radiation E_1 , which is highly penetrable, penetrates the layer 100 to excite the photoconductive layer 5. Thus, the photoconductive layer 5 is excited by two energy images, i.e. the X-ray energy image and an orange light energy image, which has been formed from the X-radiation through conversion in wavelength, and to which the layer 5 is most sensitive. As the result, the photoconductive layer 5 is increased in conductivity in a plane at right angles to the direction of radiation E_1 , and a corresponding photocurrent is caused through the layer 3 to electrically excite the electroluminescent powder therein thereby to produce in the layer 3 a bright green image of the positive nature, which is amplified relative to the X-ray energy image E_1 with a sensitivity much higher than that of any conventional electrostatic image converter-amplifier.

Under this condition, if V_1 is fixed and a "dark" state is established with no radiation E_1 given, a dark current I_{10} is formed in association with V_1 , which flows between the third and first electrodes 6 and 2 through the intermediary of the electroluminescent layer 3. However, when voltage V_2 is applied, a current I_2 flows between the first and second electrodes 7 and 2 by way of the luminescent impedance layer 100, the interior of the reticular structure of the third electrode 6, and the electroluminescent layer 3.

Accordingly, if the voltage V_1 is fixed and the phase difference of the voltage V_2 from V_1 is selected so as to obtain a differential relation between the currents I_1 and I_2 , the amount of amplitude of the current $I_3=I_1+I_2$ flowing through the layer 3 and hence the dark luminescence thereof are reduced as the amplitude of the voltage V_2 increases. Such phase difference is usually selected in the range of $180^\circ \pm 90^\circ$ depending upon the impedance characteristic of the material employed. With radiation E_1 given under this condition, a visible image E_2 of the positive nature is obtained which has a contrast ratio and a gamma value both increasing with increase in amplitude of V_2 , rendering the operating characteristics variable in a wide range. Contrariwise, if V_1 and V_2 are both fixed in amplitude and the phase difference therebetween made variable, the contrast ratio and the gamma value can be controlled over a wide range in a decreasing direction as the phase relationship deviates from that for the above described differential relation between I_1 and I_2 .

Similarly, where V_2 is applied, with $V_1=0$, the current relation $I_3=I_2$ is obtained and the layer 3 is effectively excited with the current I_2 . Under this condition, if radiation E_1 is given, the photoconductive layer 5 increases in conductivity in accordance with the distribution pattern of the local strength of E_1 . It will be noted that, since the electrodes 2 and 6 are at the same potential, the layer 5 behaves as an electrostatic shielding layer and the current I_2 is bypassed through the third electrode 6 to reduce

the current $I_3=I_2$, which is flowing through the layer 3. In this manner, radiation E_1 is converted, while being intensified, into a bright visible image E_2 of the negative nature relative to radiation E_1 .

Under this condition with radiation E_1 , if the phase difference of V_1 from V_2 is selected to obtain the differential relation of I_1 (ordinarily in the range of $180^\circ \pm 90^\circ$), the contrast ratio and the gamma value are increased as the amplitude of V_1 is increased from zero. On the other hand, as the phase difference is varied to deviate from the differential relation while fixing the amplitude of V_1 and V_2 at a properly adjusted value, the contrast ratio and the gamma value are reduced accordingly. In the case of V_1 has a more or less large amplitude, the deviation of the phase difference causes reduction in contrast ratio and gamma value thereby to obtain a visible image E_2 as a mixture of a negative image corresponding to those portions of the image E_1 which are limited in intensity and a positive image corresponding to the high intensity portions of the image E_1 . Where the phase difference between voltages V_1 and V_2 gives an additive relationship between currents I_1 and I_2 , an image E_2 of the positive nature shows itself which is entirely reverse to the one described above.

Assume that the amplitudes of V_1 and V_2 are selected so as to obtain a nearly differential relationship between I_1 and I_2 and to render I_3 predominant over I_2 when dark with no radiation E_1 and over I_1 when a radiation E_1 of a uniform and high intensity is given.

Under this condition, if an X-ray energy image E_1 of a sufficiently high intensity is irradiated while maintaining I_1 and I_2 in a differential relation in which I_1 and I_2 are in phase and of the same amplitude, the output image E_2 obtained is extremely limited in brightness in areas corresponding to the localized intensity of the X-ray energy image E_1 and is of the negative nature in areas corresponding to those regions of the X-ray image having an intensity lower than said localized intensity and of the positive nature in areas corresponding to those regions of the intensity higher than said localized intensity. In this manner, the X-ray energy image is divided into two groups of intensity regions and is converted into an image of a combined negative and positive nature. In other words, the device exhibits a so-called V-shaped operation characteristic. In this case, if the amplitude of V_1 is increased or that of V_2 decreased, the V-shaped characteristic is shifted in a direction in which the strength of the input X-ray radiation increases, and similarly, if the amplitude of V_1 is decreased or that of V_2 increased, the V-shaped characteristic is shifted in a direction in which the X-ray radiation decreases in strength. Thus, the behavior of the output image E_2 can be freely varied simply by controlling the amplitudes of V_1 and V_2 , and precise observation and examination of the X-ray energy image E_1 can be performed by a kind of zero method.

On the other hand, if, with the amplitudes of V_1 and V_2 fixed, the phase difference therebetween is caused to deviate from the differential relationship, the minimum luminescence intensity of the output image E_2 increases to reduce the contrast ratio while displacing the V-shaped characteristic. If the phase difference between V_1 and V_2 is varied to obtain an additive relation between I_1 and I_2 , the output image E_2 varies continuously into an image of the positive nature.

As apparent from the foregoing description on several modes of operation, the inventive device is highly advantageous in that such operation can be effected continuously from one mode to another by controlling the amplitudes of the voltages V_1 and V_2 and the phase relationship therebetween. Moreover, the device can be fixed to have a V-shaped characteristic of the positive, negative or intermediate nature simply by properly fixing the voltages V_1 and V_2 .

For the continuous controlling of the device or fine

adjustment thereof in a limited range, it is preferable to employ an AC power supply source including a single signal generator and two electrical signal amplifier systems for amplification of its AC signal output with a variable phase-shifter and amplitude-controlling means arranged in at least one of the amplifier systems. As for the voltages V_1 and V_2 , however, it is not always necessary to provide a power supply source such as including two electrical signal amplifiers. The fixed or variable controlling of the voltages V_1 and V_2 can be effected with a single power supply if provided with means to open the several electrodes of the device, to insert an impedance element such as a resistor, an impedance or a capacitor or a combination of such elements between the electrodes or between the latter and the power source, or also to fix or make variable the impedance value of such impedance element or combination of impedance elements. Further, a modification in which one power supply system includes an output transformer having a tap changer or slider means on the output coil thereof may provide an entirely satisfactory amplitude relationship between the voltages V_1 and V_2 and also a satisfactory phase relationship therebetween at least in cases where the voltages are in the same or opposite phase.

Having described some forms of luminescent impedance layer 100, it is to be noted that the dielectric strength of the layer 100 often raises some problem because of the required application of voltage V_2 . Such problem, however, can be alleviated by admixing a powder of dielectric substance to the layer 100 which is light-reflecting and has a high dielectric strength. For example, the luminescent impedance layer 100 may be formed by mixing a powder of fluorescent material and a powder of highly light-reflecting dielectric substance such as zinc sulfide, zinc oxide, titanium oxide or barium titanate and laminating such mixture with a binding agent such as epoxy resin. Apparently, it is necessary to properly select a dielectric strength and an impedance value for the layer 100.

On the other hand, the luminescent material is subject to spectral limitations of the luminescent light energy and to other limitations such as the conversion efficiency of the material. Therefore, the selection of an impedance value resolves itself down to a matter of controlling the thickness of the layer. On the other hand, highly light-reflecting materials provide a considerably wide range for selection of the dielectric constant. For example, barium titanate powder has a dielectric constant of several thousands or over, and titanium oxide of the anatase form of the order of ten. Therefore, one advantage of the luminescent impedance layer 100 is that its impedance value can be selected in a wide range by properly selecting the materials therefor and changing their volume ratio in the mixture. It is to be understood that the present invention also includes within its scope such structures of luminescent impedance layer.

Though the foregoing description has been made with respect to the operation on an AC power supply, the voltages V_1 and V_2 may also be of DC form in cases where the electro-luminescent layer 3 takes the form of an evaporated film such as of ZnS activated with Mn or other element, since such layer 3 is luminescent with a DC power supply. In such cases, various modes of operation as described hereinbefore can be obtained by controlling the voltage values and their polarity.

Also in these cases, it is obvious that the various component layers of the device must be formed to have a proper conductivity to allow a more or less DC current flow therethrough.

This can be accomplished by properly selecting the materials including binding agents for the layers, or by properly controlling their volume ratios, or also by admixing a proper low resistance material or materials thereto.

The luminescent impedance layer 100 should also be formed in the above manner. However, for X-ray energy

images, which are highly penetrable, an appropriate conductivity can be obtained without detracting from the utilization of the luminescent light energy by admixing a powder of highly light-reflecting metal such as silver in a proper volume ratio.

Description will next be made on another embodiment of the present invention, which is shown in FIG. 2 and formed upon the basis of the same principles as the one shown in FIG. 1.

The embodiment of FIG. 2 is basically similar to the radiant energy responsive display device of FIG. 1, but is particularly adapted for use with radiation energy in the form of a beam of electrons.

For convenience in description, the solid disc portion 15 of the device is generally indicated at 200 and the power source means for applying voltages V_1 and V_2 at 300. The reference numeral 400 indicates an envelope similar to the picture tube used in a television set. The solid disc 200 being arranged in a portion corresponding to the 20 fluorescent screen in the latter. An electron gun 401 emits a beam of electrons E_1 , which is modulated by an electrical signal S. Reference numeral 402 indicates an electron beam deflecting coil.

If, with voltages V_1 and V_2 applied, an electron beam 25 E_1 is directed onto the second electrode 7, which is comprised, for example, of an evaporated, aluminum film and is electron-beam transmitting, the electron beam penetrating through the second electrode 7 excites the luminescent impedance layer 100, which includes at least a 30 cathode luminescence material and when excited emits light energy, which excites the photoconductive layer 5. In this manner, it will be understood that the luminescence output E_2 of the electroluminescent layer 3 can be controlled electrically.

35 For example, if a video signal is used as electrical signal S to control electron beam E_1 , it can be converted into a visible image image, which appears on the first electrode (2) side of the assembly under control of the deflecting coil 402.

40 This embodiment is thus operable in the same manner as conventional television picture tubes and, exhibiting a much higher amplification factor, can operate satisfactorily with an electron beam E_1 lower in voltage and current and with a video signal S weaker than any conventional television picture tube. In addition, the output 45 image obtained with the device is brighter because of its higher amplification.

An extremely important advantage of this device is that not only the contrast ratio and the gamma value of 50 the image can be freely controlled by varying voltages V_1 and V_2 , as described above, but an output image of the negative or combined positive and negative nature can also be obtained with the same signal S by controlling V_1 and V_2 .

55 A further embodiment of the present invention shown in FIG. 3 is particularly adapted for use with a radiation energy image E_1 such as an ultraviolet image, which is relatively low in penetrability.

A major feature of this embodiment is that its luminescent impedance layer 100 is of composite form.

Description will now be made assuming that E_1 is an ultraviolet image. In FIG. 3, reference numeral 101 indicates a luminescent layer at least containing photoluminescent material such as CdZnS:Ag, which emits orange 65 light when excited with ultraviolet image E_1 . The layer 101 can be formed in the same manner as described in connection with FIG. 1. When excited, the layer 101 can luminescence only in its surface region since the ultraviolet image E cannot fully excite the interior of the layer 70 because of its limited penetrability.

Therefore, the excitation of photoconductive layer 5 is effected by the luminescence light energy coming from the surface region of the layer 101 therethrough and such excitation may not be satisfactorily effective because 75 the light energy is partly lost by absorption during its

passage through the material of the layer 101. To avoid this, the layer 101 itself should be made extremely thin.

On the other hand, the thickness of the layer 101 is subject to limitations from the impedance and dielectric strength requirements to the layer 100 as a luminescent impedance layer.

This situation can be improved by employing an auxiliary luminescence light energy transmitting impedance layer 102 between the luminescent layer 101 and photoconductive layer 5. The impedance layer 102 is formed of a transparent low-loss dielectric substance, such as a polyester film or a light-transmitting glass enamel. With this construction, the problems of the impedance and dielectric strength can be met with the layer 102, allowing the layer 101 to have any desired thickness. The light energy produced in the layer 101 when excited by ultraviolet image E_1 passes through the layer 102 to effectively excite the photoconductive layer 5, as will readily be understood.

By use of the composite luminescent impedance layer 100 including elementary layers 101 and 102, it will be appreciated that any ultraviolet image E_1 can be converted or amplified into visible images E_2 of different natures by controlling the voltages V_1 and V_2 , as described hereinbefore in connection with FIG. 1, though such image conversion is impossible with photoconductive layer 5 formed of photoconductive material such as CdS:Cu, Cl.

In this embodiment, the second electrode 7, which is radiant energy transmitting, is comprised of a base or support plate, such as a quartz plate 14, which is transmissive to radiant energy and, in this instance, to ultraviolet rays, and an electrically conductive film of tin oxide or the like material coated on said base plate 14.

The third or grid electrode 6 in this embodiment includes an arrangement of spaced parallel metal wires and a conducting strip 17, between which voltage V_1 is applied from power supply source 8, as illustrated.

The embodiment of FIG. 3 also includes another form of interlayer 13 lying between the opaque layer 4 and electroluminescent layer 3. The layer 13 is designed to prevent dielectric breakdown between the electrodes 2 and 6 and also to reflect the luminescence light from layer 3 thereby to enhance the brightness of the visible output image E_2 . The layer 13 may be formed by evaporating a high dielectric white substance having a high reflection factor and a high dielectric strength, for example, titanium oxide or barium titanate, or by laminating a mixture of a powder of such substance and a binding agent such as glass enamel or plastic.

The thickness of the interlayer 13 is determined so as to give an impedance lower than that of layer 3 with the intention of reducing the voltage loss.

The wire grid electrode 6, serving as a discharge electrode, includes tungsten or other metal wires of the thickness of the order of 10 to 150μ arranged at regular intervals of the order of 250 to 700μ and, if required, plated with gold.

In this example, the grid electrode 6 is formed of thin tungsten wires of the thickness of about 10μ and is embedded in the relatively thick layer 5 midway of its thickness of about 80μ .

It will be understood that this embodiment is also usable on the same principles with radiation energy E_1 taking the form of X-rays, γ -rays or like radiant rays of high penetrability. With electron beams, satisfactory results can be obtained by eliminating base plate 14 and making electrode 7 in the form transmissive to electron beams, for example, in the form of an evaporated aluminum film.

FIG. 4 illustrates another embodiment of the present invention which is particularly useful with radiation energy forms of high penetrability such as X-rays and γ -rays. In this embodiment, the luminescent impedance layer 100 is also a composite layer, but of the construction different from that in the embodiment of FIG. 3.

Description will now be made on the embodiment as used with a radiation energy E_1 in the form of an X-ray image.

In FIG. 3, the photoconductive layer is excited by luminescent light rays which have passed through the impedance layer 102, which is transmissive to luminescent light energy. In that case, the light rays are often dispersed in the layer 102 to such an extent as to make output image E_2 hazy.

This difficulty is overcome in the embodiment of FIG. 4 by laying directly on the surface of the photoconductive layer 5 a luminescent layer 101 which at least contains a radiation luminescence material as one mentioned hereinbefore. A radiant energy transmitting auxiliary impedance layer 103 is provided between the second electrode 7 and layer 101, as illustrated, for the purpose of improving the dielectric strength and impedance characteristics of the assembly. The auxiliary impedance layer 103 in the illustrated example is formed of an X-ray transmitting dielectric substance such as polyester or other plastic film, glass film or glass enamel.

The second electrode 7 is an X-ray transmitting electrode which is light-reflecting with an aluminum or other metal film evaporated or an aluminum or other thin metal foil stuck thereon. Also, utilization may be made of an electrically conducting film of a metal oxide such as tin oxide coated on a thin base plate of glass.

In addition, an appropriate light reflectivity may be imparted to the layer 103 to enhance the utilization factor of luminescent light energy from the layer 101. In other words, the layer 103 may be made radiation energy transmissive and luminescent light energy reflecting to serve as an auxiliary impedance layer. For example, for use with X-ray images, the layer 103 should leastwise contain a highly light-reflecting substance. One example is a single layer of magnesium oxide or like material coated on the luminescent layer 101. Another example takes the form of a mixed layer including a fine powder of zinc sulfide, titanium oxide, barium titanate or like compound mixed with a binding agent such as epoxy resin or other plastic or glass enamel.

With these forms of composite layer 103, the luminescent light energy from layer 101 is subjected only to a minimized light-dispersing effect and can be utilized in the photoconductive layer 5 efficiently enough to form a clear and definite output image E_2 , since it is directly reflected by the layer 103 toward the photoconductive layer 5. These forms of composite layer 103 are obviously highly transmissive to X-rays since they are usually made considerably thin.

In the case where the layer 103 is transmissive to luminescent light energy and the latter is reflected by the second electrode 7, as described hereinbefore, the light energy must proceed over a substantial distance and is subject to a considerably high light-dispersing effect in the layer 103. This sometimes causes an unnegligible detraction from the quality of the output image E_2 .

If the layer 103 is made opaque or light absorptive in an attempt to eliminate such adverse effect, it will absorb the luminescent light rays and the utilization factor of the luminescent light energy and hence the sensitivity of the device will be reduced correspondingly.

It follows, therefore, that to impart a light reflectivity to the layer 103 is a very effective way to save this difficulty.

The use of impedance layer 103 is also advantageous when viewed from the standpoint of controlling its impedance value in that an appropriate impedance value can readily be selected for the layer while improving the dielectric strength thereof by properly selecting the thickness of the layer and, if it is a mixed layer, the specific dielectricity and volume ratio of the powder materials forming the layer.

The power supply system shown in FIG. 4 is particularly well adapted to control the operation characteristics of the inventive display device direct-currentwise over a

widely extended range while improving the sensitivity thereof, in case the device includes a photoconductive layer 5 in the form of a mixed layer including photoconductive powder material such as CdS:Cu, Cl and a binding agent such as epoxy resin and is driven by an AC power source 300.

The third electrode 6 is comprised of an arrangement of electrically conductive metal or like strips or metal wires. In FIG. 4, the electrode 6 is shown as an electrode including metal wires and is embedded in the luminescent impedance layer 100 and held in electrical contact with the photoconductive layer 5. The wires of the third electrode 6 are connected with conductive strips 71 and 72 in an alternate fashion, forming two mutually insulated electrodes, which are connected with a variable current source 16 by way of a polarity changing switch 15 and with an AC power source 300 by way of direct-current blocking capacitors C_1 and C_2 and a conductor 10. Capacitors C_1 and C_2 should have a capacitance sufficient to minimize their AC impedance.

As illustrated, the AC power source 300 applies an AC voltage V_1 between conductors 9 and 10 and another AC voltage V_1 between conductors 9 and 12. Under this situation, AC voltage V_1 is applied between the third electrode 3 and light-transmitting electrode 2, and DC voltage V_B between the two sets of alternate elements in the third electrode 6 (in the plane of the photoconductive layer 5 extending at right angles to the direction in which the X-ray energy E_1 is irradiated).

The AC photoconductive sensitivity of the photoconductive layer, which is formed of a mixture of photoconductive powder such as CdS:Cu, Cl with a binding agent, as described hereinbefore, is reduced as the frequency increases because of the nonlinearity of its voltage-current characteristics and inherent AC dependence. This reduction in AC photoconductive sensitivity can be ameliorated by use of a DC controlling voltage.

On the other hand, the sensitivity, operation characteristics contrast ratio and gamma value of the radiant energy responsive display device shown in FIG. 4 are dependent upon the photoconductive sensitivity in a plane normal to the direction in which E_1 is irradiated. Therefore, these characteristics of the device can be made variable by use of DC voltage V_B from the variable DC power source 16 to controllably increase the AC photoconductive sensitivity in a plane normal to the direction of radiation E_1 . The range of variation in the performance characteristics will be extended as the voltages V_1 and V_2 increase in frequency.

In the positive, V-shaped and negative operations of the device as obtained by controlling V_1 and V_2 in the same manner as described in connection with FIG. 1, the increase in V_B causes displacement of the operation characteristics in a direction in which the irradiation magnitude of the input radiant energy decreases thereby to increase the sensitivity, contrast ratio and gamma value. An important advantage is thus obtained that the range of variation in performance of the device which is obtainable by controlling the amplitude and phase relationships of V_1 and V_2 (including the case where either V_1 or V_2 is reduced to zero) can be further extended under the control of DC voltage V_B .

On the other hand, use of a photoconductive layer formed of powdery material bound together is very undesirable for some applications since even after the irradiation of the radiant energy image has been interrupted the speed of response is so limited as to cause a residual image continuing for a period of from several seconds to several minutes.

Utilizing a special phenomenon of this form of photoconductive layer, the residual image can be extinguished rapidly by changing the polarity of the D.C. voltage V_B , which is being applied between the interlined electrodes 6, thereby to reverse the polarity of the D.C. electric field in which the photoconductive layer 5 is placed.

The polarity-changing switch 15 is provided to serve the purpose. With the power supply system shown in FIG. 4, it will thus be appreciated that not only the performance characteristics of the display device can be made variable over a wider range but also the residual image can be freely extinguished.

This power supply system can be applied irrespective of the structure of the third electrode 6 as long as it includes an arrangement of electrode elements, for example, as shown in FIG. 3, and without regard to the type of radiant energy image E_1 .

Obviously, voltage means 16 is not always required to be variable since the D.C. voltage may be fixed if required.

Though the luminescent impedance layer 100 has been shown and described herein as including one or two layers, it may take the form of a composite layer including more than two elementary layers without departing from the spirit of the invention.

It will be appreciated from the foregoing that the present invention makes it possible to convert a radiant energy image into a visible image intensified with high sensitivity, which has previously been impossible or feasibly only with limited sensitivity.

The radiant energy responsive display device of the present invention is usable with a wide variety of radiant energy images: including those having wavelengths shorter than the highest sensitivity wavelength in the spectrum or conductivity distribution of the photoconductive layer, whether they are visible or invisible (like ultraviolet rays); radiation energy images such as X-ray or γ -ray radiation images; electron radiation images or signals such as electron beams; and all other radiant energy signals or images effective to excite the luminescent impedance layer 35 of the device. Particularly, with high penetrability radiation energy images such as X-ray or γ -ray images, the inventive device can operate with such a high sensitivity as has previously been unimaginable since the photoconductive layer is excited with two types of image including 40 the radiant energy image passing through the luminescent impedance layer and a luminescent light energy image formed under the excitation effect of the radiant energy image.

Though a few embodiments of the present invention have been shown and described herein, it is to be understood that many changes and modifications can be made by combining the features and concepts of the different embodiments without departing from the spirit of the invention or from the scope of the appended claims.

What is claimed is:

1. A radiant energy responsive display device of the type including a photoconductive layer, an electroluminescent layer lying on one surface of said photoconductive layer, an impedance layer lying on the other surface of said photoconductive layer, a first electrode arranged on the outer surface of said electroluminescent layer, a second electrode arranged on the outer surface of said impedance layer, a third electrode interposed between said electroluminescent and impedance layers in electrical contact with said photoconductive layer, electric power supply means for applying a first voltage between said first and third electrodes and second voltage between said first and second electrodes, an means for electrically controlling the luminescent intensity of said electroluminescent layer through the variation in impedance under the excitation effect of radiant energy on said photoconductive layer to thereby convert a radiant energy image into visible form on said electroluminescent layer, in which said impedance layer is an energy converting luminescent layer having a radiant energy response to a first spectral distribution and having a luminescence characteristic with a second energy distribution different from the first and at least partly overlapping the spectral photoconductivity distribution of the photoconductive layer whereby, when excited with radiant energy,

said luminescent impedance layer produces luminescent light energy to which said photoconductive layer is responsive.

2. A radiant energy responsive display device according to claim 1 wherein an intermediate layer is interposed between said electroluminescent layer and said photoconductive layer.

3. A radiant energy responsive display device according to claim 1 wherein said intermediate layer is an opaque layer.

4. A radiant energy responsive display device according to claim 1 wherein said first electrode is a light transmitting electrode.

5. A radiant energy responsive display device according to claim 1 wherein said second electrode is a radiant energy transmitting electrode.

6. A radiant energy responsive display device according to claim 1 wherein said third electrode is a grid-like discharge electrode.

7. A radiant energy responsive display device according to claim 1 wherein said radiant energy image is converted to visible form on said electroluminescent layer at a size no less than that of the original image.

8. A radiant energy responsive display device according to claim 1 in which the maximum spectral sensitivity of said photoconductive layer lies within the spectral range of the luminescence of said luminescent impedance layer.

9. A radiant energy responsive display device according to claim 1 in which said luminescent impedance layer has a thickness of 20 to 200 μ .

10. A radiant energy responsive display device according to claim 1 in which said impedance layer comprises a compound of zinc and epoxy resin.

11. A radiant energy responsive display device according to claim 1 in which said impedance layer comprises a compound of zinc and glass enamel.

12. A radiant energy responsive display device according to claim 1 in which said impedance layer comprises a highly light reflective material.

13. A radiant energy responsive display device according to claim 1 in which said impedance layer comprises a mixture of powder of a luminescent material and a binding material.

14. A radiant energy responsive display device according to claim 1 comprising an auxiliary impedance layer capable of transmitting said luminescent light energy produced by said impedance layer interposed between said impedance layer and said photoconductive layer.

15. A radiant energy responsive display device according to claim 1 comprising an auxiliary impedance layer capable of transmitting said radiant energy interposed between said impedance layer and said second electrode.

16. A radiant energy responsive display device according to claim 1 comprising an auxiliary impedance layer capable of transmitting said radiant energy and capable of reflecting said luminescent light energy produced by said impedance layer interposed between said impedance layer and said second electrode.
